TIRE

Michael Tiborcz, 714 W. Market St., Akron, Ohio

Filed Mar. 14, 1961, Ser. No. 64,271

Term of patent 14 years

(Cl. D90—20)

FIG. 1

FIG. 3

FIG.2

FIG. 1 is a perspective view of a tire embodying my new design, it being understood that the full-line portions of the tread are repeated throughout the circumference of the tire shown by means of broken lines, and the full-line portions of the side walls are repeated throughout the circumference of the side walls shown by broken lines;

FIG. 2 is an enlarged plan view of the tread portion thereof;

FIG. 3 is an enlarged sectional view thereof taken on the line 3-3 of FIG. 2; and

FIG. 4 is an enlarged fragmentary elevational view of the side wall thereof, the opposite side being essentially the same.

I claim:

The ornamental design for a tire, as shown and described.
